ATTORNEY

UNITED STATES PATENT OFFICE.

JOHN BOYD HAYES, JR., OF PEGRAM, TENNESSEE.

AIR-CONTROL DEVICE FOR CARBURETORS.

Application filed November 27, 1922. Serial No. 603,651.

This invention relates to an improved carburetor, a general object of the invention being to simplify the construction and to provide means whereby the gas is thoroughly mixed with the air.

Another object of the invention is to provide an air supply which is particularly controlled by the speed of the motor.

This invention also consists in certain other features of construction and in the combination and arrangement of the several parts, to be hereinafter fully described, illustrated in the accompanying drawings and specifically pointed out in the appended claim.

In describing my invention in detail reference will be had to the accompanying drawings wherein like characters of reference denote like or corresponding parts in the several views, and in which:—

In the drawings:—

Figure 1 is a longitudinal section view of the invention.

Figures 2 and 3 are detail views.

In these views 1 indicates the float chamber which contains the float 2 and which is connected with a source of supply in the ordinary manner. The bored extension 3 of the body of the carburetor passes through the center of the float chamber, the upper end of the bore 3' open out in the air chamber 4. A valve seat 5 is formed at the upper end of the bore 3' and this seat is engaged by the needle valve 6. The extension 3 provided with a pair of ports 7 which permit the gasoline in the float chamber to pass into the bore. The air chamber 4 is in communication with the air inlet 8 and after passing through the passage 9 the mixture will flow through the outlet passage 10 which contains the butterfly valve 11. The extension 3 has its upper end forming a conical depression and a conical partition 4', connected with the top of the body, depends into the said depression and the space between the walls of the depression and the partition forms the air chamber 4. This

partition also separates the air inlet 8 from the outlet passage 10. A tube 12 is arranged in the front part of the partition near the top thereof and has one end in communication with the inlet 8 and its other end in communication with the passage 10. A valve block 13 is arranged in the tube and this valve is pressed upon the pin 14 by a spring 15. The tube is provided with perforations 16 so that when the suction of the engine causes the block to move inwardly against the action of the spring some of the perforations will be uncovered and thus some of the air will pass directly into the passage 10 from the inlet 8.

It will be seen that this movement of the valve block 13 will depend on the speed of the engine so that the greater the speed of the engine the more air will flow into the passage stem. A screw plug 17 crosses the end of the bore 3' so as to permit the cleaning of the same.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In a carburetor, a partition separating the air inlet of the carburetor from the mixing chamber thereof, a perforated tube in the top part of the partition and forming a direct connection between the air inlet and the outlet, the end of the tube, toward the air inlet being open and its other end closed, a plug valve closing the open end and adapted to be moved inwardly by the suction created by the engine to expose some of the perforations in the tube, a coil spring in the tube and a pin in the open end of the tube and against which the spring holds the valve.

In testimony whereof I affix my signature.

JOHN BOYD HAYES, JR.
